2,000,773

CARPENTER'S TOOL

John B. McGlaughlin, Denver, Colo.

Application November 10, 1933, Serial No. 697,438

4 Claims. (Cl. 33—112)

This invention relates to a marking square for use by carpenters and other workers for marking the proper saw cuts necessary in the framing of roof rafters.

5 In such work it is usually necessary for the mechanic to lay out his various saw cuts mathematically or to use the complicated scales of a carpenter's square to obtain the proper miters necessary to cut on the rafters. This is a task 10 requiring much time and skill to obtain accurate miters.

The principal object of this invention is to provide a device which will instantly give the proper side and edge miters necessary to frame the ridge and valley rafters of a given roof and which 15 will also indicate the proper length for cutting the rafters for any desired span.

Another object is to so construct the device 20 that it will be economical to manufacture; rugged in construction, and easy to use.

Other objects and advantages reside in the 25 detailed construction of the invention, which is designed for simplicity, economy, and efficiency. These will become more apparent from the following description.

In the following detailed description of the 30 invention reference is had to the accompanying drawing which forms a part hereof. Like numerals refer to like parts in all views of the drawing.

In the drawing:—

Figure 1 is a front face view of the improved rafter marking square.

Figure 2 is a similar view illustrating the rear 35 face thereof.

Figure 3 is a top view thereof.

Figure 4 is a cross section therethrough taken on the vertical center line.

There are three standard pitches for the 40 ordinary pitch roof, that is, one-quarter pitch, one-third, and one-half pitch and, although the present invention can be made to suit roofs of any desired pitch, it is preferred to manufacture it in the two standard pitches, one-third and 45 one-quarter.

The drawing illustrates the form for a one-third pitch roof.

The invention comprises a face plate 1, the 50 lower portion of which has a specific triangular form, to be later described, and the upper portion of which forms a straight edge 7, provided with scales 8 marked off in inches, and fractions thereof.

A squaring plate 3 projects outwardly from one 55 face of the plate 1. The plate 3 may be secured

to the plate 1 in any desired manner or may be an integral part thereof if desired. As illustrated, the two plates are joined by means of tongues 6, formed on the plate 3, projected through and riveted in suitable openings in the plate 1. The plate 3 projects perpendicular to the surface of the plate 1 and parallel to the straight edge 7.

The triangular portion of the plate 1 is formed with two similarly inclined edges 9 each of which forms an angle with the squaring plate 3 equal to the plumb or ridge angle of a rafter having $\frac{1}{3}$ pitch. Two inclined slots 2 are formed in the triangular portion of the face plate. These slots form an angle with the squaring plate 3 equal 15 to the angle of the main or plumb cut on a hip or valley rafter in a roof having a $\frac{1}{3}$ pitch.

The squaring plate 3 also contains two pairs 20 of inclined slots. The first or outer pair 4 form an angle with the face plate 10 equal to the bevel or edge cut on the upper end of a rafter. The other pair of slots 5 form an angle with the face plate equal to the bevel or edge cut on a 25 hip or valley rafter.

To mark the position of the saw cut on the 30 upper extremity of a common or jack rafter, the squaring plate 3 is placed against the upper edge of the rafter at the mark indicating the long side thereof, and a mark is drawn across the rafter along the inclined side 9. This gives the 35 exact position for the top or plumb cut of the ordinary rafter. Should the rafter come against a hip or valley rafter, it will of course be necessary to make a bevel cut in addition to the plumb cut. The mark for this bevel cut is obtained by marking along the slot 4. For hip or valley rafters, the plumb cut is obtained by marking along the slot 2, and the bevel cut is obtained by marking the edge of the rafter along the slot 5. Since the device carries similar 40 edges and similar slots on both sides of its center line, the device can be used for marking the rafters on both sides of the ridge.

The device is also useful for marking the 45 plate and gutter notches. In marking the plate notch, the squaring plate 3 is placed against the lower edge 11 which will indicate the depth of the notch. The device is then reversed so that the triangular portion will over-lie the rafter with the squaring plate against the upper edge 50 thereof, and the plumb cut of the notch is drawn along the proper edge 9. The intersection of the plumb mark with the depth mark will give the point of the notch. The corners of the 55 squaring plate are rectangular and are used as

a square to obtain the horizontal cut mark of the notch. The same procedure is used for hip or valley rafters except that the slots 2 are used for obtaining the plumb cut or vertical mark.

5 It will be noted that the diagonal edges 9 and the slots 2 carry "key" numbers, the number on the diagonal edges being "14.42" and the number on the diagonal slots being "18.76." These numbers are used for obtaining the proper 10 length to cut any desired rafter, and are obtained mathematically from the angle formed by the given roof pitch. The numbers illustrated are for a $\frac{1}{3}$ pitch roof for which the illustrated device is intended. To use the key numbers, the mechanic multiplies the horizontal 15 distance in feet between the ridge of the roof and the plate upon which the lower extremity of the rafters is to rest or $\frac{1}{2}$ the roof span by the key number. This will give him the exact 20 length in inches from the apex of the rafter to the vertical plumb mark of the plate notch. For main rafters, the key number on the diagonal sides is used. For hip and valley rafters the key number on the diagonal slots is used.

25 A one-third pitch roof rises 8 inches in a span of 12 inches. The key number is therefore the square root of the sum of the squares of 8 and 12 or $14.42 +$. The key numbers for other pitches are similarly obtained.

30 While a specific form of the improvement has been described and illustrated herein, it is desired to be understood that the same may be varied, within the scope of the appended claims, without departing from the spirit of the invention.

35 Having thus described the invention, what is claimed and desired secured by Letters Patent is:—

1. A rafter marker comprising: a face plate; 40 a squaring plate projecting perpendicularly from said face plate; a pair of diagonal edges formed in said squaring plate and inclined toward each other, each of said edges forming an angle with said face plate equal to the bevel cut on a

rafter of a certain given pitch; and a second pair of diagonal edges formed in said squaring plate, each of said second pair of edges forming an angle with the face plate equal to the bevel cut on hip and valley rafters of the same specific pitch. 5

2. A rafter marking device comprising: a face plate; a squaring plate projecting at right angles from the rear face of said face plate; a pair of diagonal, opposite edges on said face plate, each of said edges forming an angle with said squaring plate equal to the proper plumb cut for a rafter of a given pitch; a pair of diagonal edges formed in said squaring plate and inclined toward each other, each of said edges forming an 15 angle with said face plate equal to the bevel cut on a rafter of a certain given pitch.

3. A rafter marking device comprising: a face plate; a squaring plate projecting at right angles from the rear face of said face plate; a pair of diagonal, opposite edges on said face plate, each of said edges forming an angle with said squaring plate to the proper plumb cut for a rafter of a given pitch, and a second pair of edges inset from said first pair, each of second pair of edges 25 forming an angle with said squaring plate equal to the angle of the plumb cut on hip and valley rafters of the same given pitch; and a second pair of diagonal edges formed in said squaring plate, each of second pair of edges forming an 30 angle with the face plate equal to the bevel cut on hip and valley rafters of the same specific pitch.

4. A rafter marking device comprising: a face 35 plate; a squaring plate projecting at right angles from the rear face of said face plate; a pair of diagonal, opposite edges on said face plate, each of said edges forming an angle with said squaring plate equal to the proper plumb cut for a rafter of a given pitch; the width of said 40 squaring plate being equal to the depth of the plate notches in said rafters.
